UNITED STATES PATENT OFFICE.

STEPHEN T. SMITH, OF STAMFORD, CONNECTICUT, ASSIGNOR TO UNDERWOOD TYPE-WRITER COMPANY, OF NEW YORK, N. Y., A CORPORATION OF DELAWARE.

COPY-HOLDER.

1,203,659.

Specification of Letters Patent.

Patented Nov. 7, 1916.

Application filed May 8, 1914. Serial No. 837,146.

To all whom it may concern:

Be it known that I, STEPHEN T. SMITH, a citizen of the United States, residing in Stamford, in the county of Fairfield and 5 State of Connecticut, have invented certain new and useful Improvements in Copy-Holders, of which the following is a specification.

This invention relates to copy holders, and 10 particularly to those which are adapted to rest upon a desk or table.

The principal object of the invention is to provide a copy holder which is stable in use so as not to be subject to undue vibration from the operation of a typewriting or 15 other machine to which the copy holder may be an adjunct; to produce a device which will not be noisy nor liable to be accidentally overturned, and which may, by simple 20 means, be instantly adjusted to any one of a series of working positions, whereby the operator may conveniently adjust the copy holder to the desired angle; also to produce a copy holder having some or all of these 25 advantages, and which can be readily reduced to small compass for convenience in transportation or storing; and further to produce a device of this class which will be inexpensive, and which may also, if occasion 30 arises, be used as a receptacle for sheets or typewriter supplies.

In carrying out my invention, I produce a structure generally resembling a large shallow oblong box, the bottom and sides 35 of which may constitute the base of a copy holder, and the top of which may be hinged at one end to said base so as to be readily liftable to form a copy-holding plate, board or table; this plate preferably having at its 40 sides and top down-turned flanges for stiffness and neatness, and said flanges being of a size and position to fit between the sides and ends of the box or base when the device is folded together. In other words, the base 45 may constitute one box and the copy-holding plate, which is hinged thereto, may constitute an inverted box to fold down within the base box.

An arm is hinged to the copy-holding 50 plate, and may be swung to different positions to hold the copy-holding plate, board or table at different angles; a rack being provided on the base to be engaged by said leg when required, thereby to sustain the

copy-holding plate in any desired position. 55 Said arm may be in the form of a bail, and said rack may be in the form of ears struck up from the body of the base at opposite sides thereof to be engaged by said bail. When the device is collapsed or folded, the 60 bail may lie snugly between the downturned flanges of the copy-holding plate or table, the cross-bar of the bail lying just within the flange at the upper end of said plate, and the two rows of struck-up lugs being within 65 the bail. The bottom of the base may be muffled by a layer of felt, and this layer may cover the holes left in the base by striking up said lugs therefrom.

There is also preferably provided at the 70 bottom of the copy-holding plate a ledge upon which the copy may rest; the ledge preferably having a roughened surface for the copy to rest upon. This ledge may be hinged upon the same plate that hinges the 75 copy plate to the base, whereby the ledge may be folded up upon the copy plate so as not to project when the latter is folded down into the base box.

Other features and advantages will here- 80 inafter appear.

In the accompanying drawings, Figure 1 is a perspective elevation of my improved copy holder, in extended position for use. Fig. 2 is a longitudinal sectional view of the 85 device, as closed. Fig. 3 is an enlarged detail sectional view of the hinged portion of the device. Fig. 4 is a perspective view of the connecting portions of the base and copy-holding plate members of the device, 90 and the ledge, showing these members disassembled. Fig. 5 is a partial sectional view of the hinged portion of the device, with the corrugated ledge extended for use and Fig. 95 6 is a sectional view of a modified base cov- ering.

As premised, the device which is the subject of this invention consists essentially of a copy-holding member having a base member which will support the entire structure 100 in a stable manner to the end that it may not be influenced through the vibrations arising from the operation of a typewriting machine when standing upon a typewriter desk for use in conjunction with the machine. Said base member may consist of a flat plate 1 with side walls 2, front end wall 3 and rear end wall 4. The bottom of

plate 1 may be covered with felt or other soft material 5, capable of holding snugly to a desk or table surface or other support, and to prevent vibrations, which may be communicated to support from the operation of a typewriting machine carried thereby, from creating objectionable noise, and from disturbing the copy. This bottom covering of soft material may for convenience 5 be in form of a thin sheet of stiff material 6, covered with baize or the like, as at 7, (see Fig. 6), said sheet being secured to the bottom of plate 1 as by fastenings 8.

The copy holder is composed of a plate 9 having side walls 10 and rear end wall 11, being pivoted at the forward ends of its side walls 10 to the forward ends of side walls 2 of the base member, as by stub shafts 12, forming a hinged engagement between said 10 base member and copy holder. The width of the copy holder is less than the width of the base member, that the walls of the former may nest within the walls of the latter, in closing, thereby saving space and enabling said hinged members, when folded together, to form a closed receptacle for 25 sheets of paper or other supplies.

Pivoted in bosses 13 secured to the side walls 10 of the copy holder member, in opposed relation, are the out-turned ends 14 of bail arms 15 whose opposite ends merge into a transverse bail 16, capable of folding snugly against the inner surface of the copy holder, or of extending outwardly to find lodgment upon the inner surface of the base member to thereby support the copy holder in an upward position.

To provide such lodgment for the bail there may be a rack upon the inner surface 40 of plate 1 and I have provided a suitable rack by striking inwardly from the material of said plate, two opposite series of lugs 17, the inclination of the incisions which result in the production of the lugs being inwardly 45 and forwardly from lines parallel with the side walls 2, whereby said lugs, from the process of their production form forwardly inclined teeth which arrest the bail 16 in the various set positions occupied by opposed 50 pairs of said lugs, to thereby sustain the copy holder member in any desired angle of adjustment for the convenience of the user. The lugs 17 are arranged sufficiently near to their respective walls 2 to leave ample width 55 of space between them for the accommodation of sheets of paper or the like to be contained therein when the copy holder is to be used as a receptacle. A ledge, as 18, is hinged at the forward end of plate 9, the 60 ledge and plate having the alternate hinge portions 19 connected by a pintle 20. As thus hinged to the plate 9, the ledge 18 may be folded flat upon the upper surface of said plate, or may be swung outwardly at right angles thereto in the per-

formance of its function as a support for the lower edges of the copy sheets. The ledge 18 has rearwardly extending wings 21, and the plate 9 has inturned portions 22, said wings 21 and portions 22 being arranged in coinciding pairs and meeting as the ledge is swung outwardly to form a stop to limit that movement. The ledge 9 may be roughened, as with the corrugations 23, or otherwise, to afford a secure holding 70 surface wherewith to retain the lower edges of copy sheets thereon. When the bail is folded against the plate 9, it will, in the closing of the two hinged portions of the receptacle, lie at either end thereof with its arms 75 intermediate the rows of lugs 17 and the adjacent walls 10 which latter are then nested in walls 2.

It will be apparent from the foregoing description, that I provide a copy holder having an ample base to stand firmly on a supporting surface, and that the device is both compact and highly serviceable.

Variations may be resorted to within the scope of the invention, and portions of the 90 improvements may be used without others.

Having now described my invention, I claim:

1. A copy holder comprising a base plate having upwardly extending walls and a 95 plate with paper supporting means thereon having downwardly extending walls of smaller dimensions, a hinge connection between said plates at one end, a bail pivoted to the second mentioned plate, a series of 100 forwardly directed lugs on the inside bottom of the base plate with which the bottom of the bail may engage in any adjusted position, the said lugs being arranged on each side of the bottom plate near the walls thereof 105 providing spaces between said lugs for storage purposes.

2. A copy holder comprising a base plate and a holder plate having paper supporting means thereon, a hinge connection between 110 said plates at the ends thereof, the holder plate being provided with downwardly extending walls and the base plates with upwardly extending walls of slightly larger dimensions whereby the holder plate may 115 nest within the base plate, a wire bail hinged to the holder plate near the middle thereof and formed at its free end to constitute the foot of the said bail, the bottom of the base plate being provided with forwardly directed 120 lugs struck up from said bottom, the foot of the bail being adapted to engage with said lugs to hold the upper plate in any desired angle.

3. A copy holder comprising a base plate 125 and a holder plate, said holder plate having paper supporting means thereon and said plates having telescoping side walls, a hinge connection for said plates, a member hinged to the side walls of the holder plate and 130

means coöperating therewith to hold said holder plate in various angular adjusted positions upon said base plate.

4. A copy holder comprising a base plate formed of sheet metal and perpendicular walls therefor, a holder plate formed of sheet metal and having perpendicular walls adapted to nest within the walls of the base plate whereby the two form a receptacle, a hinge rod passing through the side walls of the base plate and of the holder plate near one end thereof, the bottom of the base plate being provided on each side near the side wall thereof with a row of forwardly projecting lugs struck up from the metal of the bottom, a wire bail pivoted at its ends thereof to the side walls of the holder plate and its foot being wide enough to extend between the rows of struck up lugs, the length of said bail being sufficiently small to enable it to be folded within the supporting plate, and a ledge pivoted to the supporting

plate at one end thereof on its top whereby a folding support for holding copy is provided.

25

5. A copy holder comprising a base plate and a holder plate, the two being hinged together near one end thereof, the holder plate being provided with a bail and the base plate with lugs with which said base plate 30 engages, whereby the two are held in any adjusted position, and a ledge pivoted to the holder plate at or near its hinged end, said ledge provided with rearwardly extended wings and said supporting plate with in- 35 turned portions adapted to be engaged by said wings whereby when said ledge is swung outwardly to form a support, the said wings and inturned portions forming a stop to limit the turning movement.
